SAFETY LATCH

Aaron Shatkin, Matawan, N. J.

Application January 10, 1944, Serial No. 517,647

6 Claims. (Cl. 24—162)

1

The present invention relates to latches particularly adaptable to articles of jewelry employing a pin for a fastening means, as on brooches and the like.

An object of this invention is to provide a novel and improved latch for brooches and similar articles, which is easy to lock and unlock.

Another object hereof is to provide a novel and improved latch means of the character mentioned, in which the pin point is shielded while the latch is closed.

A further object of this invention is to provide a novel and improved article of the type set forth which is reasonably cheap to manufacture, simple to manipulate and efficient in carrying out the purposes for which it is designed.

Other objects and advantages will become manifest as this disclosure proceeds.

To accomplish these objects, essentially, a pivoted pin is otherwise moveably mounted on a frame carrying a socket for receiving the free end of the pin which is pointed, and means to prevent movement of the pin when within the socket.

In the accompanying drawings forming part of this application, similar characters of reference indicate corresponding parts in all the views.

Fig. 1 shows a closed latch embodying the teachings of this invention, partly in section.

Fig. 2 is a plan view of Fig. 1; the latter being a view which also may be described as a section taken along lines 1—1.

Fig. 3 shows said latch in open condition.

Fig. 4 is a perspective view of the pin-point socket employed in the article illustrated.

Fig. 5 is a side view of Fig. 4.

Fig. 6 is a view similar to Fig. 3 of another embodiment of this invention.

Fig. 7 shows the article of Fig. 6 in closed condition, partly in section.

In the drawings, the numeral 10 designates an ornament carried on a frame indicated generally by the numeral 11, which has associated therewith a swingable pointed pin 12, for attachment to a wearer's garment for instance. One end of the pin 12, is pivotally secured at 13 to a link 14, while the other end of said pin is adapted to be received and housed in member designated generally by the numeral 15. The link 14 is provided with a longitudinal slot 16, through which is positioned a pin 17, secured at its ends in a pair of bracket members 18 which are part of the frame. It is evident that the link 14 is both slideable and swingable about said pin with respect to the frame element 11'. The frame also includes 19, which serves as a socket or track to receive the

2

link 14 therein and maintain same against rotary movement about its axis pin 17. The element 20, may be so bent in slight convergent relationship with element 11', that the fit of link 14 in said socket is snug when shifted therein manually which may be facilitated by the tab 14'. A second tab 14'' extending from said link, serves to limit the movement of the pointed pin 12 about its axis pin 13. The free end of element 20 and element 11' serve to limit the scope of rotary movement of the link 14 about its axis pin 17.

The pin point housing 15, has a guide slot 15' which leads the point pin 12 into socket bore 15''. It is to be noted that axis pin 17 is intermediate the pin point socket 15 and the link socket 19, in close proximity to the latter. The tininess of the various elements and particularly in some constructions, the springiness of the pin member 12, permits proper operation of this latch, whose mode of use will now be set forth.

Taking hold of the article in condition as shown in Fig. 3 when the pin 12 is free of socket 15, and link 14 is not engaged within socket 19, and in position substantially normal to frame 11', said pin is laced in the usual manner through a fabric garment and swung about pin 13 so that the pointed end thereof may be placed within slot 15' of the housing 15 which shall guide its movement into the socket bore 15''. By turning the link 14 now, so that it shall lie in alignment with pin 12, said link will enter its socket 19. The latch is now in closed condition as illustrated in Fig. 1; the article is securely worn, and the point of pin 12 is safely housed. To open the latch and remove the article from the wearer, take hold of tab 14' and slide the link out of socket 19, whereby pin 12 will move further into its socket bore 15' which is purposely made long enough for such purpose, and when said link 14 is free of member 20, it is swung away from frame element 11' again into position as in Fig. 3, whereupon pin 12 will withdraw from socket 15, and the latch will be open for withdrawal of pin 12 from wearer's garment.

In the embodiment illustrated in Figs. 6 and 7, the pin 22 is pivotally mounted at 23 to a link 24, which in turn is pivotally mounted to the bracket 28. The axis pin 23 also carries thereon pivotally mounted, a cam member 26 which is adapted to be shifted by handling prong 26', so that said cam frictionally engage the bracket member 28 to lock the pin against movement after the pointed end of the latter is set within the socket member 15. The frame member is here indicated by the numeral 21.

By turning cam 26 away from engagement with the bracket member 28 of the article of Fig. 7, the latch may be opened.

For purposes of definition in the claims, the bracket members 18 and 28, may be deemed as part of their respective frames.

This invention is capable of numerous forms and various applications without departing from the essential features herein disclosed. It is therefore intended and desired that the specific description herein be deemed illustrative and not restrictive, reference being had to the following claims rather than to the particular embodiments herein to indicate the scope of this invention.

I claim:

1. In an article of the character described, a frame, a link, means on the frame holding said link in swingable and slidable relation to the frame, a pin pivotally secured at one of its ends to the link; the axes of rotation of the pin with respect to the link and of the link with respect to the frame being parallel, a member having a socket carried by the frame; the free end of the pin being adapted to be positioned within said socket; and an element carried by the frame in engagement with said link whereby the link is held against rotary movement and against sliding movement away from the socket; said link being adapted to be slid towards the socket until released from the engagement element and free for rotary movement about its axis on the frame; the pin, when its free end is within the socket, moving further into the socket during movement of the link away from the engagement element, and the pin becoming free of the socket, upon movement of the link about its axis on the frame in a direction away from said socket.

2. An article as defined in claim 1, including a stop means carried by the link in the locus of movement of the pin with respect to said link; said stop means being adapted to restrain rotary movement of the pin about its pivotal connection on the link.

3. An article as defined in claim 1, wherein the pin socket element is provided with an entrance slot communicative with the socket bore; said entrance slot lying in the locus of movement of the end portion of the free end of the pin.

4. An article as defined in claim 1, wherein the link is comparatively short and the pin is comparatively long.

5. An article as defined in claim 1, wherein the link engagement means is a resilient element forming with the frame a U shape of which the frame and part of said element are the arms, whereby upon the entrance of the link between the arms of said U shape said link is snugly gripped by said arms.

6. In an article of the character described, a frame, a link having a longitudinal slot, an axis pin fixedly mounted on the frame and positioned through the slot, whereby the link is slidable on said axis pin in a direction normal to the axis of said axis pin, and swingable about said axis, a pin pivotally secured at one of its ends to the link; the axis of rotation of the pin with respect to the link and of the link with respect to the frame, being parallel, a member having a socket carried by the frame; the free end of the pin being adapted to be positioned within said socket; and an element carried by the frame in engagement with said link whereby the link is held against rotary movement, and against sliding movement away from the socket; said link being adapted to be slid towards the socket until released from the engagement element and free for rotary movement about its axis on the frame; the pin, when its free end is within the socket, moving further into the socket during movement of the link away from the engagement element, and the pin becoming free of the socket, upon movement of the link about its axis on the frame in a direction away from said socket.
